METHOD OF MEASURING FLUID FLOW

Lawrence L. McWilliams, Bartlesville, Okla., assignor to Phillips Petroleum Company, a corporation of Delaware

Application January 17, 1941, Serial No. 374,943

2 Claims. (Cl. 73-51) 73-155

This invention relates to the measurement of fluid flow and more particularly to a method of measuring the amount of fluid that is flowing through various types of passages, including well bores, oil well tubing, and the like.

Within the past few years it has become common practice in the production of hydrocarbon fluids to apply water-flood methods of secondary recovery to the reservoir after it has been depleted of its natural energy. The water introduced into a hydrocarbon oil reservoir more thoroughly cleanses the sand grains of their oil and moves the oil toward the producing hydrocarbon oil wells. At the present time, surface waters and waters produced to the surface of the ground are usually employed for water flood operations. However, waters that are cased off and sealed from the hydrocarbon oil formation may be used for water flood purposes if some method of measuring the amount of water that would flow into the hydrocarbon oil formation could be obtained. The water introduced into a hydrocarbon oil formation should be measured, as it is desirable for the operator to know at all times the conditions which affect the water-flood operation. If the water introduced is beyond control of the operator, the results would be reduced benefits and possibly great injury to the hydrocarbon oil wells.

My present invention provides a method of measuring water which may be injected from an upper water-bearing strata into a lower hydrocarbon oil-bearing strata through the same well bore; thus, allowing the operator to control the water-flood of the hydrocarbon oil-bearing formation.

The primary object of my invention is the provision of a method of measuring the amount of fluid flowing through various types of passages, including well bores, oil well tubing, and the like.

Another object of my invention is to provide a method of measuring fluid flow in substantially vertical conduits by measuring a differential in force, caused by a loss of fluid head occasioned by fluid flowing past a restriction in a conduit.

Other objects and advantages will be readily apparent to persons skilled in the art by reference to the following description and annexed drawing which pertain to preferred embodiments of my invention; wherein,

Figure 1 is an elevation view of one embodiment of my invention, partly in cross section; and

Figure 2 is an elevation view, partly in cross section of another embodiment of my invention. Referring to the drawing, and more particu-

larly to Figure 1 thereof, I have denoted an oil well casing 10 with perforations 11 opposite a water-bearing sand 12. Within this casing, a tubular member 13 is suspended below a surface closure 14 and extends downwardly to an oil-bearing formation 15. Mounted concentrically on tubing 13 is a packer 16 which seals the annular space 17 below the perforations 11. A plurality of perforations 18 are provided in a working barrel 19 and are located at any desirable point above water formation 12, depending upon the hydrostatic head of water in this formation. A removable cylindrical plug 20, which is smaller in diameter than the internal diameter of working barrel 19, is suspended within the working barrel by a cable 21. The peripheral surface of the plug and the internal surface of the working barrel constitute an orifice through which water flows from the water-bearing sand to the oil-bearing sand. The cable 21 extends upwardly from plug 20 through a stuffing box 22 which is employed to prevent foreign matter from entering the tubing. The upper end of the cable is attached to indicating equipment 23 which consists essentially of any well known type of weight measuring device and a recording instrument.

In operation, packer 16 is assembled and run on tubing 13 to a point below the perforations 11. The working barrel 19 of predetermined inside diameter and having perforations 18 is part of the tubing assembly which is suspended from closure 14. Water flowing into annular space 17 rises in casing 10, depending upon the fluid head of the water-bearing strata 12. Plug 20 is secured to cable 21 and run inside of the tubing to a point directly above perforations 18. At this place, a reading on weight indicator 23 signifies the force that the removable plug exerts on the wire line and takes into account the buoyant effect of the water on the plug. The plug is next lowered into working barrel 19 to a point just below perforations 18, and another reading is taken on indicator 23. This second reading will be higher than the first, as the plug is restricting the flow of fluid. The increased load indicated on the indicator is mainly caused by the pressure drop across the orifice, although part of the increased load will be caused by an increase in head resulting from lowering plug 20 from the depth at which the first reading was taken to the depth of the second reading. By noting the increased load on the indicator, the pressure differential can be determined and converted to suitable units for calculating the volume of liquid flowing through the orifice by the

accepted basic formula. The efficiency of the orifice, which is essential to accurate calculation, may be determined by actual test at the surface of the ground. From the calculations, a set of tables may be compiled to convert weight, as indicated on weight indicator 23, into volume of water flowing into the hydrocarbon oil formation, or the weight indicator may be calibrated to read directly in barrels per day or any other suitable units.

Figure 2 illustrates another embodiment of my invention wherein parts common to both embodiments are designated by the same numerals. In the construction of this type apparatus, a hollow body 24 is constructed sufficiently heavy to overcome the friction of cups 25 which bear against the internal walls of working barrel 19, diverting the flow of water into body 24 and thence through an orifice 26.

The operation of this embodiment is identical to the operation of my first described embodiment, and the device is suspended within working barrel 19 in the same manner as heretofore described.

While I have described my invention with respect to its use in the measurement of the flow of water through tubing, it is to be understood that other fluids may be measured thereby. Its other uses include the measurement of the flow of fluids in the usual surface and subsurface conduits and it is to be noted that the direction of flow of fluid with respect to the orifice need not be only in the one direction.

From the foregoing, it is believed that the method of practicing my instant invention will be readily comprehended by persons skilled in

the art. It is to be clearly understood, however, that various changes in the method of practicing the invention, outlined above, may be resorted to, without departing from the spirit of the invention as defined by the appended claims.

5 I claim:

1. In a method of measuring the volume of fluid transmitted from a fluid-bearing formation into a second formation through a well bore that 10 communicates with both formations and that has a conduit therein, the steps comprising placing the interior of the conduit in communication with the fluid-bearing formation, providing a seal between the exterior of the conduit and the well bore at a point intermediate the formations, restricting the flow of fluid through the conduit, and simultaneously ascertaining the resulting drop in fluid pressure at the surface of the ground.

20 2. In a method of measuring the volume of water flowing from an upper water-bearing formation into a lower hydrocarbon-bearing formation through a well bore that extends through the upper formation and into the lower formation 25 and that has a conduit suspended therein, the steps comprising establishing communication between the interior of the conduit and the water-bearing formation, providing a seal between the outer surface of the conduit and the well bore at a point intermediate the formations, restricting the downward flow of water through the conduit, and simultaneously ascertaining the resulting drop in fluid pressure at the surface of the ground.
